UNITED STATES PATENT OFFICE.

ALBERT E. TOLIN, OF ANDERSON, INDIANA, ASSIGNOR TO EXCELLO MANUFACTURING COMPANY, OF CHICAGO, ILLINOIS, A CORPORATION OF ILLINOIS.

PNEUMATIC CLEANING APPARATUS.

1,123,426.

Specification of Letters Patent.

Patented Jan. 5, 1915.

Application filed December 4, 1913. Serial No. 804,704.

To all whom it may concern:

Be it known that I, ALBERT E. TOLIN, a citizen of the United States, residing in Anderson, county of Madison, and State of Indiana, have invented certain new and useful Improvements in Pneumatic Cleaning Apparatus, of which the following is a specification.

My invention relates to pneumatic cleaning apparatus, and more particularly to that type of cleaning devices in which the dust-laden air from the nozzle is caused to pass through a process of being cleaned, for instance by an air cleaning liquid, although some features of the invention are equally applicable to other types of cleaning machines.

The primary objects of the present invention are to provide air deflecting apparatus in combination with pneumatic cleaning devices whereby either suction or compression may be present at the cleaning nozzle as desired; whereby such suction or compression may be changed readily from one to the other, and, indeed, practically instantly; whereby suction or compression may readily be had in the interior of the air-cleaning receptacle, and whereby a change from one to the other therein may readily be made; whereby suction or compression at the cleaning nozzle or in the air-cleaning receptacle may be had to provide a sequence of various cleaning operations, as desired, and also whereby some of these functions may be employed individually or collectively as desired; whereby such changes in operation or function may be had without reversing or stopping the operation of the machine, and whereby they may be had without reversing the working air current in the current generating circuit, and whereby such changes may be made either at the machine itself or at a distance therefrom, as at the place, for instance, where the cleaning and renovating is being done; to provide means whereby the collected dirt in the apparatus may be forced outside the same and the dirt collecting receptacle thoroughly cleaned, and this also without stopping the machine, and without the necessity of the operators being close to it; to provide tank cleaning means which are automatic or practically automatic in operation; to provide means for maintaining a normal supply of air-cleaning liquid in the air-cleaning apparatus at all

times as desired, and also to provide such means adapted to operate automatically to such end; to provide means whereby the cleaning apparatus is preserved from back flow, as from a sewer; to provide an air-cleaning discharge nozzle adapted to co-operate with an air-cleaning liquid effectively to separate the dust and dirt from the dirt-laden current; to provide in some forms of the invention a unitary apparatus adapted to provide the advantages herein set forth, to provide apparatus of the character described which shall be of simple construction, strong and durable, compact, occupying small space, and not likely to get out of order. Still other objects will appear from the following description.

In the accompanying drawings, which form a part of this specification, I have illustrated preferred embodiments of the invention and improvement to which reference has been made, and have also shown a modification of the air deflecting apparatus constituting an important feature thereof.

Figure 1 of these drawings is a side view, partly in section, of the preferred form where the apparatus is combined in a unitary structure; Fig. 2 illustrates an electrical system adapted to control the operation of the apparatus of Fig. 1; Fig. 3 is a transverse vertical sectional view of the air deflecting valve and valve casing on the line 3—3 of Fig. 1 in the directions of the arrows; Fig. 4 is a transverse vertical section of the same valve and valve casing on the line 4—4 of Fig. 1 in the direction of the arrows; Fig. 5 is a similar view of the same parts on the line 5—5 of Fig. 1; Fig. 6 is a similar view to that of the air deflecting valve portion of Fig. 1, but showing a modified arrangement of parts; Fig. 7 is a transverse vertical section on the line 7—7 of Fig. 6 in the direction of the arrows; and Fig. 8 is a similar view of the same elements on the line 8—8 of Fig. 6 in the direction shown by the arrows.

The tank, container, or reservoir, 10 is adapted partially to be filled with an air cleaning liquid 11, such as water, the normal water line 12 of which is maintained at its proper elevation in part by means of an automatic valve 13 in association with an intake water supply pipe 14 and controlled preferably by a float 15, this automatic float valve being shown merely conventionally.

in the drawings. It will be understood that should the water 11 fall below the normal water line the valve 13 will open, permitting additional water to enter the tank until the 5 normal water line is reached when the valve will automatically close, stopping the supply.

Above the water body 11 in the tank is an air space 16 having a port or conduit 17 (see Fig. 5) leading to the interior of a valve casing 18 shown in the drawings as secured to and upon the upper wall of the tank 10 by means of bolts or screws 19'. This valve casing need not however be secured 15 directly upon the tank as suitable pipes leading from the tank to the valve casing will permit the valve to be spaced therefrom. The present arrangement is highly advantageous in the provision of a 20 unitary and compact device.

From the lower portion of the tank 10 I provide a pipe or conduit 19 leading upward to a point substantially to the normal water line where a bend is made in the pipe 25 or conduit whence the pipe extends, preferably downward, and may be connected to a waste reservoir or sewer. This conduit 19 may have a wall 20 within the reservoir as shown.

30 At a suitable place in the pipe 21, as in the top portion thereof, an automatic valve 22 is provided which may be suitably in the form of a hinged plate adapted to open when water and dirt are discharged through 35 the conduit 19 and to close should there be any back pressure from the sewer, thus preventing sewer contents from entering the receptacle 10. This arrangement of the outlet channel 19 provides also for the discharge 40 of superfluous or excess water within the tank 10, for, as is clear from Fig. 1, such excess water will flow out of the tank past the valve 22. Means are thus provided for automatically maintaining in the tank the 45 desired quantity of water for the effective operation of the device.

In the left hand side of Fig. 1 there is shown a source of suction or means 23 for providing an air current for use in the several 50 operations of the apparatus. In the intimately connected and unitary structure illustrated these means comprise a blower of any approved type, the one in the drawings being a positive blower having co-operating vanes mounted respectively on mandrels 24 and 25. This type of blower is well known and requires no detailed description. On one of the mandrels, as 25, there is provided a band wheel 26 driven by a belt 27 passing over the pulley 28 of an electric motor 29 secured upon the casing 10, as by the bolts 30. Electric current being supplied to the motor it is obvious that an air current will be produced by the blower through the rotation 35 of the wheel 26.

A pipe or suitable means 31 providing an air passage extends from the valve casing 18 to the source of air current 23, the pipe 31 shown in the drawings being suitably secured to the valve casing by means of the 70 connection 32.

Beneath the blower I preferably provide a settling chamber 33 in communication, by means of an opening or conduit 34, with the interior of the blower chamber. This settling-chamber 33 is defined by suitable walls 35 and is adapted to permit dust-like particles or any foreign matter in the air current to settle to the bottom thereof, should a material quantity of such dust or heavy 80 matter pass out of the tank through some accident or untoward occurrence with respect to the working of the machine. It also gives opportunity for such lighter particles of dust to settle as may find their way 85 through the water 11 as when carried by small bubbles emanating from the air discharge openings of the discharge nozzle, as 42. From the settling chamber, in the preferred construction, a conduit 36, which may suitably have a wall 37 thereof within the tank 10, leads to the valve casing 18 where it communicates with the interior of the valve casing through a suitable port 38 (see 90 Figs. 1 and 4).

A service pipe 39 is connected with the valve casing 18, and its hollow interior communicates with the air deflecting valve chamber through a suitable port 40 in the chamber wall. This service pipe 39 (of which only a fragment is shown) is the pipe which leads to some part or parts of a building, such as the several floors of a hotel, where it is desired to do cleaning by pneumatic means from time to time, branches of the pipe or the pipe 39 itself being provided at intervals with suitable means for connecting operatively in communication with the pneumatic cleaning apparatus flexible pipes or tubes which terminate respectively in cleaning nozzles. The extensions of the pipe 39, the connections mentioned, the flexible hose and the cleaning nozzles, and the use of such nozzles are all well understood in the art and these parts not shown are merely mentioned for the clearer understanding of the functions of the pipe 39 shown in the drawings.

Within the receptacle 10, and, in the preferred construction, secured to the upper wall thereof, as by threading the same into the boss 41, I provide an air cleaning discharge nozzle 42 having its hollow interior in communication with the air deflecting valve chamber through a suitable port 43 in the chamber wall. From a point at or somewhat below the normal water line 12 this pipe or nozzle 42 is divided transversely as by means of a saw cut or cuts on diametric lines, preferably two cuts being made 130

at right angles to each other, although these saw cuts or separations of the pipe wall may be variously directed or the nozzle may be otherwise provided with similar comparatively narrow apertures. In the preferred construction, having divided the pipe as mentioned, the divided portions of the pipe are bent outwardly, the lower portion of the pipe or nozzle thus being flared. There is thus provided a plurality of air discharging apertures 42' quite narrow at the top where there is less water for the air to pass through and gradually widening toward the bottom. It will thus be seen that should dust-laden air pass downward in a current through the pipe 42 it will find escape beneath the surface of the water through the apertures 42' and will be washed by the water so that it will emerge into the air space 16 free or substantially free of dust and dirt.

Much trouble has been experienced with means heretofore suggested for freeing the dust-laden air of its objectionable elements owing to the fact that such suggested means permit the air current to form large bubbles in the air cleaning liquid which bubbles carry with them large quantities of dust and dirt and discharge them into the air chamber before the water in the tank has had opportunity to moisten and absorb the same. The difficulties heretofore experienced have given rise to the provision of even elaborate devices for preventing the large bubbles referred to, but the presence of strings, shavings, matches and similar gleanings of the suction nozzle has rendered such devices practically useless. By the simple means here suggested these difficulties are effectively overcome.

It is to be noted that while in the present example the slotted portion or nozzle proper of the discharge conduit 42 flares slightly, its effective cross sectional area does not greatly exceed that of the upper part of the conduit. As a result the dust-laden air passes out through the slots with a velocity at least as great, approximately, as the rather high velocity with which it travels in the unslotted portion of the conduit. This produces violent agitation of the cleaning liquid, causing considerable spray in the tank above the liquid line; and this spray effects an additional washing of the air.

In the preferred construction a cylindrical shaped valve, as 50, is positioned so as to rotate or rock in the valve chamber of the valve casing 18. Figs. 1, 3, 4 and 5 show this valve 50 in the same relative position, which may be termed the normal operative position for producing suction at the cleaning nozzle, which means the provision of a downward air current in the pipe 39 in the relative position of the parts illustrated. The valve 50 is formed with suit-

able ports, the arrangement of which will be readily understood from a showing of their functions respectively in operation.

We will consider then that the source of air current 23 is causing an air current to flow toward it in the pipe 31. By reference to Fig. 5 it will be seen that by means of the port 51, formed by cutting away a segmentary portion of the end of the valve, communication is had between the source of air current 23 and the air chamber 16 of the tank 10, through the passageway 31' of the pipe 31, the port 51 and the port or conduit 17. The tendency to create a vacuum in the chamber 16 by drawing air therefrom causes air to issue from the slots 42' in the discharge nozzle 42, and by means of the port 52 in the valve 50 air is caused to flow in the service pipe 39 (see Fig. 3), causing suction at the cleaning nozzle. By reference to Fig. 1 it will be seen that the air current passes from the source of air current into the conduit 36 and reaches the port 38. By reference to Fig. 4 it will be noted that the air current now passes through a port 53 in the valve 50 and is discharged through the port 54 of the valve casing and into the pipe 55 connected thereto, or the current may be discharged directly into the open air from the discharge port 54. This arrangement and position of the valve is therefore suitable as stated for cleaning by suction at the cleaning nozzle.

Suppose now it be desired to have compression in the service pipe 39 so that dust and dirt may be blown by the cleaning nozzle from crevices or from fabrics or surfaces not susceptible of being cleaned by suction. The valve 50 is given substantially a one-eighth turn in an anti-clockwise direction from the positions shown in Figs. 3, 4 and 5. Looking at Fig. 5 it will be noted that the gateway or port 17 will now be closed by a portion 50^a of the valve 50 which is not cut away and at the same time the intake opening or port 56 will be opened so that communication will be had therethrough to the passageway 31' of the pipe 31 and thus to the source of air current 23. After passing through the blower the air current again reaches the port 38 through the pipe 36. By looking at Fig. 4 it will be plain that when the valve 50 has been given substantially a one-eighth turn in an anti-clockwise direction the port 57 (not in communication with the port 33) will be in communication with the port 38.

Turning to Figs. 1 and 3 it will be noted that the port 57 (shown for convenience of illustration as a trough-like depression in the face of the valve 50) extends to and opens into the port 52, and, considering that the valve 50 of Fig. 3 is given substantially a one-eighth turn in an anti-clockwise direction, it is plain that the air current will pass

from the port 38 to the port 52 where it is free to ascend the pipe 39 (owing to the enlargement 52' of the port 52) or descend into the discharge nozzle 42 through the 5 port 43. Inasmuch, however, as the discharge of the water 11 through the discharge conduit 19 involves considerable pressure, the air will naturally ascend the pipe 39 and provide an outwardly flowing stream 10 at the cleaning nozzle.

With the valve 50 in this one-eighth-turn position the tank 10 may be emptied and cleaned by closing a valve in the flow through the pipe 39, as at the cleaning nozzle, but it will be observed that if the valve 15 is now given another one-eighth turn in an anti-clockwise direction the air flow will in all respects be the same as in the initial one-eighth-turn position except that the port 20 40 leading into the pipe 39 will be closed. Thus in this third position of the valve air is taken at the intake 56 (Fig. 5) and discharged through the air cleaning discharge nozzle 42 and no air ascends the pipe 39.

25 It will be noted that the direction of the current in the air current generating apparatus or in the passageways, as 31' and 36, is not changed during any of the operations. This is an important feature as it is seldom 30 possible to reverse the operation of a blower and do effective work, and, furthermore, much time is saved by continuing the blower steadily at work while the various cleaning operations are being done. Numerous other 35 advantages will be obvious to persons skilled in the art.

In the modification of Figs. 6, 7 and 8 there is a single port 56' adapted for the intake from and outlet to the open air. The 40 valve is shown in the normal operative position for cleaning by suction. It will be seen that the air current entering the valve 60 through the port 38 will travel through the port 61 (Fig. 7) and be discharged 45 through the opening 56'. When the valve 60 is given a quarter turn in an anti-clockwise direction air is taken in at 56', the port 17 is closed (see Fig. 8), the channel-like port 62 is in communication with the port 38, and the current flows into the port 52, which is shown as two straight-through 50 ports crossed in the middle and at right angles to each other. In the several figures on Sheet 2 of the drawings the first eighth and the quarter turn positions of the preferred and modified forms of the valves 55 respectively are shown in dotted lines.

The valve may be operated by means of a handle 65 on the valve stem 66 suitably 60 packed as by the packing nut 67 on the valve casing head 68. In the preferred arrangement, however, I employ an electrical control comprising, for illustration, a pair of solenoid magnets 70 and 71, having their 65 armatures 72 and 73 suitably connected to a

lever 74 secured to the valve stem 66 so as to turn the same when either one or the other of the solenoids is energized. A switch 75 completes the circuit with the solenoids respectively and a source of electric current 76. The switch 75 as well as the switch 77 70 for starting and stopping the motor, may be positioned at or near the place where the cleaning is being done, and, owing in part to the automatic functions mentioned the 75 operator may thus from a distant point start and stop the motor, get air suction or compression at the cleaning nozzle and at will thoroughly clean out the tank, and all without any thought as to the water supply 80 in the tank or other heretofore bothersome features of the operation of pneumatic cleaning apparatus. The many advantages of the invention set forth will be readily appreciated by those skilled in the art.

85 While I have thus illustrated and described preferred and modified constructions and arrangements, the invention is not limited to the specific arrangements or constructions shown, and all changes and variations 90 therefrom are contemplated by me as fall within the scope of the appended claims.

I claim:

1. In pneumatic cleaning apparatus, the 95 combination of means adapted to provide a suction current and a compression current, a service pipe, a cleaning tank, a single valve in communication with said service pipe, said tank and said current-providing means, said valve being adapted to place 100 either such suction current or such compression current in communication with said service pipe and tank, whereby either suction or compression may be had in said service pipe and tank simultaneously.

105 2. In pneumatic cleaning apparatus, the combination of means adapted to provide a suction current and a compression current, a cleaning tank for dust-laden air, an air inlet thereto, a single valve in communication 110 with said tank and with said current-providing means adapted to place said tank in communication with either such suction current or such compression current, whereby either suction or compression may be had 115 therein.

3. In pneumatic cleaning apparatus, the 120 combination of a cleaning tank, a service pipe, a source of air current, and a unitary air-current deflecting device, means establishing communication between said service pipe and the open air through said tank, said source of air current and said current-deflecting means whereby suction may be had in said service pipe and tank, said current-deflecting means having provisions 125 whereby in another operative position of the same communication is established between the open air and said service pipe through said source of air current and said 130

current-deflecting means whereby compression may be had in said service pipe.

4. In pneumatic cleaning apparatus, the combination of a service pipe, a dust collecting tank, a source of air current, air current deflecting apparatus, said air current deflecting apparatus comprising a valve casing, a valve element operatively positioned in said casing, said casing having a plurality of ports in communication with the outer air (one thereof being in such communication through said service pipe) said casing having a plurality of ports in communication with the interior of said tank and having a plurality of ports in communication with said source of air current, said valve element having a plurality of ports providing communication from certain of said casing ports to others thereof in different operative positions of said valve element, the arrangement being such that in one operative position thereof an air current generated at said source of air current will flow through said service pipe, into said tank and be discharged into the open air, and in another operative position of said valve element an air current generated at said source will flow from the open air and be discharged into a valve port in communication with said service pipe, the direction of the air flow at said source of air current being constant.

5. In pneumatic cleaning apparatus, the combination of a tank adapted to contain a quantity of air cleaning liquid, a service pipe adapted to have communication with the interior of said tank beneath the normal liquid line thereof, a source of air current adapted to provide a blowing current on one side thereof and a suction current on another side thereof, air deflecting apparatus, each side of said source of air current being in communication with said air deflecting apparatus through suitable ports therein, the interior of said tank and said service pipe being also in communication with said air deflecting apparatus through suitable ports therein, said air deflecting apparatus having an operative valve element, said valve element being provided with suitable passage ways adapted to provide communication to the interior of said tank with one side of said source of air current when the valve element is in one operative position and with the other side thereof when in another operative position, whereby either suction or compression may be had in said tank through the operation of said valve element, said air deflecting apparatus having an open air port adapted to be in communication through a port in said valve element with the suction side of said source of air current when compression is applied to the interior of said tank and having another port adapted to be in communication

with the flowing side thereof through a port in said valve element when suction is applied to the interior of said tank.

6. In pneumatic cleaning apparatus, the combination of means adapted to separate dust from dust laden air, a current-deflecting valve, a service pipe, means establishing communication between said service pipe and said dust-separating means through said valve in two operative positions of said valve, means adapted to provide a suction current and a blowing current, means establishing communication between the open air and said dust-separating means through said current-providing means and said valve in one operative position of said valve, said valve having provisions whereby in another operative position thereof said current-providing means is in communication therethrough with the open air and said service pipe and dust separating means, the construction and arrangement being such that air may be drawn by suction through said service pipe and said dust separating means and be discharged from the cleaning apparatus, or be drawn from the outer air and be discharged simultaneously into said dust separating means and said service pipe.

7. In pneumatic cleaning apparatus, the combination of a valve casing, a valve element operatively within said casing, a collecting tank, means providing a plurality of passage ways connecting the interior of said casing with the interior of said tank, said casing having a plurality of openings in communication with the outer air, pipe-like means connecting one portion of the interior of said casing with another portion thereof, said valve element having a port adapted to permit air to pass from one of said outer air openings (this being an intake opening) to the interior of said tank through one of said passage ways, said valve element having a port adapted to permit air to pass from said pipe-like means into the open air through another of said outer air openings.

8. In a pneumatic cleaning apparatus, the combination of a collecting tank, means adapted to provide an air current, air current deflecting means, said deflecting means comprising a casing, valve-like means operatively positioned in said casing, said casing having ports in communication with the open air, ports in communication with said collecting tank and ports in communication with said source of air current, said valve-like means being adapted to provide passage ways between casing ports in two operative positions of said valve-like means, the arrangement of said ports being such that in one operative position of said valve-

- like means an air current may flow through one of said ports in communication with the open air, said port thus being an intake port, and into said tank, thence through 5 said means adapted to provide the air current, and thence into the open air, and in another operative position of said valve-like means the air current may flow from the open air through another of said ports 10 in communication with the open air, through said source of air current and be discharged into said first mentioned port in communication with the open air, whereby said port which was first an intake port is changed 15 to an outlet port.
9. In pneumatic cleaning apparatus, the combination of a collecting tank, means adapted to provide an air current, air current deflecting means, said deflecting means 20 comprising a casing, valve-like means operatively positioned in said casing, said casing having ports in communication with the open air, and ports in communication with said collecting tank, said casing having 25 a port in communication with each of the respective sides of said source of air current, said valve-like means being adapted to provide passage ways between casing ports in three operative positions of said valve- 30 like means, the arrangement of said passage ways being such that in one operative position of said valve-like means an air current may flow through one of said outer air ports and into said tank, thence through 35 said means adapted to provide the air current, and thence into the open air, and in another operative position of said valve-like means the air current may flow from the open air through another of said open 40 air ports, through said source of air current and be discharged simultaneously into said tank and into said first mentioned open air port, and in a third operative position of said valve-like means the air current may 45 flow from the open air through an open air port, through said source of air current and be discharged into said tank.
10. In pneumatic cleaning apparatus adapted to separate dust from dust-laden 50 air, the combination, with a tank adapted to contain an operative amount of an air-cleaning liquid, a discharge conduit adapted to carry dust-laden air entering said tank and having a nozzle portion extending below 55 the normal liquid line therein, the cross sectional area of such nozzle portion being approximately not substantially greater than that of said conduit, said nozzle portion being provided with relatively long 60 slot-like apertures longitudinal with the nozzle at a portion thereof below the normal liquid line in said tank, said apertures being substantially V-shaped, said apertures being adapted to permit dust laden air to escape from the nozzle in gradually en-

larging streams as the air current proceeds through that portion of the nozzle containing said apertures.

11. In pneumatic cleaning apparatus, the combination of a tank adapted to contain 70 an operative quantity of an air-cleaning liquid, an air discharge pipe adapted to carry dirt-laden air extending into said tank and below the normal liquid line thereof, said discharge pipe being provided with 75 relatively long and narrow substantially vertically disposed longitudinal slot-like apertures on a portion thereof lower than the normal liquid line in said tank, such portion having an effective cross sectional area 80 not greatly in excess of the effective cross sectional area of the remainder of the pipe.

12. In pneumatic cleaning apparatus, the combination of a tank adapted to contain 85 an air-cleaning liquid, an air discharge pipe adapted to carry dirt-laden air extending into said tank and below the normal liquid line thereof, said discharge pipe being provided with longitudinal slot-like apertures 90 on a portion thereof lower than the normal water line, the lower portion of said pipe having its walls cut transversely and flared apart.

13. In cleaning apparatus, the combination of a service pipe, a unitary valve-like 95 air current deflecting device in communication with said service pipe, a collecting receptacle in communication with said deflecting device, an air current generating device in communication with said air deflecting 100 device and adapted to be placed in communication with said collecting receptacle through the operation of said deflecting device, said generating device being adapted to provide a compression current and a suction current in said air current deflecting device, said deflecting device having provisions adapted to place said service pipe and said tank in communication with a suction current or a compression current generated by said current generating means, 105 means for operating said generating device and means for operating said air current deflecting device, the arrangement being such that either suction or compression may be 110 had in said service pipe and tank through the operation of said generating device and said deflecting device.

14. In cleaning apparatus, the combination of current generating means adapted to 120 provide a suction current and a compression current, a service pipe, a collecting tank intermediate said service pipe and said generating means, and a single valve-like air deflecting device in communication with said generating means and said service pipe, said device comprising a plurality of elements 125 adapted to coöperate with each other in different relative positions thereof, said valve-like device having provisions adapted to 130

place said current generating means, said tank and said service pipe in communication with each other in different relative positions of elements of said valve-like device, the arrangement being such that either suction or compression may be had in said tank through the operation of said generating means and said current deflecting device.

15. In cleaning apparatus, the combination of current generating means adapted to provide a suction current and a compression current, a service pipe, a collecting tank intermediate said service pipe and said generating means, said collecting tank being adapted to contain a quantity of air cleaning fluid, means adapted to discharge air from said service pipe at a point in said collecting tank lower than the plane of the normal liquid line therein, and a single valve-like air deflecting device intermediate said service pipe and said generating means and in communication with said generating

means and said tank, said air deflecting device having provisions adapted to place the interior of said tank in communication with either a suction current or a blowing current from said generating device.

16. In pneumatic cleaning apparatus, the combination of a tank adapted to contain a quantity of air cleaning liquid, a discharge nozzle adapted to extend below the liquid line of said tank, a service pipe, air suction and compression generating means, a single valve in communication with said generating means, service pipe, discharge nozzle, tank, and the open air, said valve having ports adapted alternately to place a suction current and a compression current from said generating means in communication with said service pipe.

ALBERT E. TOLIN.
